DOORFRAME

Fredrick H. Waltermann and John P. Malmrose,
Kewanee, Ill., assignors to Kewanee Manufacturing Company, Kewanee, Ill., a corporation of Illinois

Application December 4, 1951, Serial No. 259,786

3 Claims. (Cl. 189—46)

1

Our invention relates to doorframes and more particularly to doorframes of steel or other suitable metal.

An object of our invention is to provide a new and improved metal doorframe which is more attractive than those now in use.

Another object of our invention is to provide a new and improved metal doorframe which is more adaptable than those now in use.

Another object of our invention is to provide a new and improved metal doorframe which affords greater protection to the edge of the plaster or dry wall.

Another object of our invention is to provide a metal doorframe having a new and improved shape.

Another object of our invention is to provide a new and improved metal doorframe which is designed for attachment directly to the rough door buck or studding which is standard in interior wall constructions for homes and offices.

Another object of our invention is to provide a new and improved metal doorframe so constructed that the weight of the door is carried entirely by the rough door buck or studding.

Another object of our invention is to provide a metal doorframe having a novel recess construction for receiving the door hinges.

Another object of our invention is to provide a new and improved metal doorframe which will permit a door mounted on standard hinges to pivot to a position parallel to the wall in which the door opening is located.

Another object of our invention is to provide a metal doorframe having a new and improved construction for receiving a door strike or latch.

Another object is to provide a metal doorframe having a new and improved interlocking connection between the several parts thereof.

Other objects and advantages will become apparent as the description proceeds.

In the drawings:

Fig. 1 is an elevational view of a door and door opening with the frame embodying our invention mounted in the opening;

Fig. 2 is a perspective view of the upper end of one of the vertical side pieces of our novel frame;

Fig. 3 is a similar view of an end of a top or horizontal piece embodying our invention;

Fig. 4 is a perspective view of the upper corner of the door opening having our novel frame mounted therein and illustrating the manner in which the door is hinged mounted;

Fig. 5 is a partial sectional view on an enlarged scale taken on the line 5—5 of Fig. 1;

2

Fig. 6 is a view similar to Fig. 5 but showing the door in closed position;

Fig. 7 is a horizontal sectional view taken on the line 7—7 of Fig. 1, showing the parts on an enlarged scale;

Fig. 8 is a partial section taken on the line 8—8 of Fig. 1 and showing the strike plate and box for preventing plaster, dust, etc., from coming out of the latch opening in the metal frame;

Fig. 9 is a partial vertical section taken on the line 9—9 of Fig. 8; and

Fig. 10 is a partial sectional view taken on the plane of the line 10—10 of Fig. 9 but showing the door in closed position.

In Fig. 1 we have shown our novel doorframe as being comprised of three pieces consisting of vertical side pieces 20 and 22, and a horizontal top piece 24. The lower ends of the side pieces 20 and 22 are illustrated as resting on the finished floor 26 although they can be extended below the finished floor and the finished floor fitted around them if preferred. The side pieces 20 and 22 and top piece 24 are of identical cross section as will be more readily apparent from an inspection of Figs. 2, 3, 4, and 7. Each of these pieces is formed from sheet steel or other suitable material and may be formed from relatively thin and inexpensive sheets because our novel frame does not carry any of the weight of the door and is so constructed that the exposed edges are reinforced.

Each piece has a longitudinal rib 28 provided with parallel sides equidistant from the center line of the strip or piece and capable of constituting a door stop when the door is mounted on either side of this central rib. In Fig. 7 the door is shown as mounted on the near side of the central rib but a feature of our novel design makes it possible to mount the door on the far side of the central rib. This could be accomplished by interchanging side pieces 20 and 22 and this can be accomplished without disturbing the top piece 24. On opposite sides of the central rib 28 are planar panels 30 and 32 of equal width. The width of each of these panels is approximately equal to the thickness of a standard door for the interior wall of a home or office building. Beyond the planar panels 30 and 32 are inclined corner panels 34 and 36 whose outwardly extending edges 38 and 40 are strengthened by bending the metal back upon itself to provide a double thickness. Leg portions or perpendicular strips 42 and 44 connect the central portions of the corner panels with flanges 46 and 48 which engage the sides of the 2 x 4's form-

ing the rough door buck or studding which is a standard part of the interior wall construction.

In Fig. 7 the right-hand rough door buck is shown as being composed of two 2 x 4's 50 and 52 nailed back to back. This is the most common construction, although in some instances only the 2 x 4 identified by the reference character 56 would be used in order to reduce expense. In the left-hand side of Fig. 7 we have shown a different and superior rough buck construction which is also standard practice and wherein the 2 x 4's 54 and 56 are arranged side by side with a spacing strip 58 therebetween so that the thickness of the buck in a sidewise direction is the same as that of the buck shown in the right-hand part of Fig. 7. In all of these standard forms of rough buck construction the flanges 46 and 48 engage opposite sides of the buck and are attached thereto by nails 60 or in any other suitable manner.

The door 62 may be of any standard or suitable construction and may be mounted on standard door hinges 64. One leaf 66 of each hinge may be attached to the door by screws 68, whereas the other hinge leaf 70 fits into a recess 72 pressed in the side piece 22. The recesses 72 are pressed into the side piece 22 without interrupting the continuity of the metal of which the side piece is formed, the only break in the metal being the three small holes through which the screws 74 pass. It will be noted that these screws go directly into the rough buck which supports the entire weight of the door so that none of this weight is carried by our novel metal frame.

In Figs. 6 and 7 we have shown the door in closed position, whereas in Figs. 4 and 5 we have shown the door in fully open position. It will be noted that with a standard size of door hinge, the door may be swung to a position parallel to the wall in which the door opening is located. This is advantageous in that it permits the door to be placed in a convenient out-of-the-way position while at the same time making available the full width of the door opening for moving furniture or other articles therethrough.

The side piece 20 is similarly recessed to receive a strike plate 76, best shown in Figs. 8, 9, and 10. This strike plate is secured to the metal frame piece 20 by screws 78 which pass through openings 80 in the frame piece 20 and into threaded bores in a reinforcing strip 82 and a metal box 84. The reinforcing strip 82 is spot welded to the frame piece 20 as indicated at 86. The strike plate 76, frame piece 20, and reinforcing strip 82, have aligned openings 88, 90, and 92 which permit the door latch 94 to extend through an open side of the box member 84 as indicated in Fig. 10. This box is formed of a strip of metal of generally U-shaped cross section and having a turned down flap 96 closing the rear of the box, the front being left open as indicated at 98. This box serves the purpose of preventing pieces of plaster or other material from falling down and interfering with the door latch 94 or from falling through the opening in the strike plate and dirtying the floor.

Referring to Figs. 2, 3, and 4, it will be seen that we have provided a novel and effective interlocking engagement between the vertical sides 20 and 22 and the horizontal or top portion 24 of the frame. As best shown in Fig. 2, the central projecting rib 28 of each side piece is made shorter than the rest of the side piece, whereas the rib 28 of each top piece projects at each end to form an interlocking tongue. The upper ends of the

side pieces 20 and 22 and both ends of the edge panels 34 and 36 of the top piece 24 terminate in miters which form the mitered joints 100 and 102, best shown in Fig. 4. This figure also clearly shows the manner in which the rib 28 of the top piece 24 overlies the rib of the side piece 22. Because the frame pieces are symmetrical about their longitudinal axes, the surfaces forming the miter joints 100 and 102 are at the same angle with respect to the axes of the frame pieces. This facilitates assembly and increases the adaptability of our frame construction to various needs since either end of the top piece will fit the top of either side piece.

In order to strengthen each end of each frame piece, a reinforcing strip 104 is spot welded thereto as best shown in Fig. 3.

Our novel frame construction is equally adapted for use with either a dry wall construction or a plaster wall of any of the various types. In Fig. 7 we have shown the wall 106 as being of dry construction and the wall 108 as of plaster construction. In each instance it will be noted that the edge of the wall adjacent the door opening is securely protected by a folded-over frame edge of double thickness and that this frame edge is firmly supported by a leg portion 42 or 44, both of which directly engage the studding defining the door opening. This design eliminates the necessity of plaster holes, gives a full length plaster bond on both sides of the wall, and eliminates plaster cracks or distortions produced by prior art frame constructions.

From the foregoing it will be apparent that we have provided a novel frame construction which is inexpensive to manufacture, easy to install, adaptable to a wide variety of needs, and having an attractive appearance and configuration more nearly resembling that of the conventional doorframe of wood construction. While our novel frame is primarily intended for interior wall constructions, it can be used as an exterior wall doorframe provided the wall construction surrounding the door opening is made of appropriate thickness to fit between the flanges of our doorframe or a doorframe of special size is made for exterior wall constructions.

It is to be understood that our invention is not limited to the details shown and described but includes all modifications, variations, and equivalents coming within the scope of the appended claims.

We claim:

1. A substantially symmetrical, metal doorframe piece adapted to be applied as a moulding to a wooden doorframe which includes a rectangular buck having a width of approximately four inches formed from a single sheet of metal and having a substantially centrally located doorstop rib bent forwardly from the main body of the piece, said main body including lateral webs extending at right angles to the rib on both sides thereof and providing duplicate door-receiving surfaces which, with the central rib, are at least equal in extent to said width of the buck, the remote margin of each such web then being bent rearwardly at an oblique angle to provide a bevel facing, then forwardly against said facing, and then connecting with a flange that extends rearwardly at right angles to said door receiving surfaces for attachment to said wooden doorframe, said flange being substantially in alignment with the juncture of said web and said bevel facing, whereby said door-receiving surfaces may lie parallel to and closely adjacent to the adja-

cent face of the buck over which the doorframe piece is to be mounted.

2. A symmetrical doorframe piece as set forth in claim 1 in which door hinge receiving recesses are embossed in one of said door receiving surfaces, and in which screw holes are provided whereby screws used for fastening hinge leaves in place within said hinge recesses will directly engage the buck for supporting the door directly from said buck.

3. A symmetrical metal doorframe piece as set forth in claim 2 in which a door latch opening is provided in one of the door receiving surfaces, and a latching box rigidly fixed to the inner face of said door receiving surface in alignment with said door latch opening.

FREDRICK H. WALTERMAN.
JOHN P. MALMROSE.
